Primary Examiner — Kevin K Rudzinski*Assistant Examiner* — Paul D Bohannon(74) *Attorney, Agent, or Firm* — Dykema Gossett PLLC(57) **CLAIM**

The ornamental design for a cabinet, as shown and described.

DESCRIPTION

FIG. 1 is an elevational front view of a cabinet showing my new and ornamental design,

FIG. 2 is an elevational rear view thereof,

FIG. 3 is an elevational right side view thereof,

FIG. 4 is an elevational left side view thereof,

FIG. 5 is a top plan view thereof,

FIG. 6 is a bottom plan view thereof,

FIG. 7 is a perspective right front view thereof; and,

FIG. 8 is a perspective left front view thereof.

The broken lines in FIG. 6 represent features of the cabinet which form no part of the claimed design.
